UNITED STATES PATENT OFFICE.

ALFRED S. HENN, OF NEW HAVEN, CONNECTICUT, ASSIGNOR TO SARGENT & CO., OF SAME PLACE.

SNAP-HOOK.

SPECIFICATION forming part of Letters Patent No. 250,533, dated December 6, 1881.

Application filed October 28, 1881. (No model.)

To all whom it may concern:

Be it known that I, ALFRED S. HENN, of New Haven, in the county of New Haven and State of Connecticut, have invented a new Improvement in Snap-Hooks; and I do hereby declare the following, when taken in connection with the accompanying drawings and the letters of reference marked thereon, to be a full, clear, and exact description of the same, and which said drawings constitute part of this specification, and represent, in—

Figure 1, a side view; Fig. 2, top view; Fig. 3, longitudinal section; Fig. 4, transverse section of the hook complete; Figs. 5 and 6, the two parts detached; Fig. 7, transverse section of the body on line $\alpha\alpha$, looking toward the loop.

This invention relates to an improvement in that class of snap-hooks in which a bolt is arranged longitudinally in the body to slide back and forth from the point of the hook to open and close the mouth, and the said bolt provided with a spring, the tendency of which is to force and hold it forward against the end 25 of the hook to close the mouth, yielding for the opening of the hook.

The object of the invention is to avoid the mechanical labor necessary in the manufacture of this class of hooks as usually constructed, and also to cast the parts without a core; and the invention consists in the construction of the hook, as hereinafter described, and particularly recited in the claim.

As seen in Fig. 5, the body A is constructed with the loop B at one end and the hook C at the other end, in the usual relation to each other, the hook C being turned to one side out of its natural plane, so that it may be readily molded, also in the usual manner. The body 35 A has a longitudinal opening, D, in the vertical plane of the hook—that is, downward through the body—and on each side of this opening is an inwardly-projecting rib, a, which forms the longitudinal guide for the bolt. 40 Across the opening, or in rear of it, is a bridge, b, as a seat for the spring.

Fig. 7 shows a section of the body of the hook on line $\alpha\alpha$ of Fig. 5, in which the ribs a and the bridge b are clearly seen. This completes the body of the hook. It is of such

shape that it may be readily molded and cast complete, so that the subsequent "tumbling" operation finishes that part except the bending of the hook up into its natural plane.

The bolt, as seen in Fig. 6, has its body E 55 of tubular shape, with a longitudinal transverse slot, e, through it, the diameter of this tube corresponding to the width of the opening D in the body of the bolt, and the slots in the opposite sides correspond to the ribs a a, 60 so that the plate may be passed longitudinally into the opening D onto the guides a a and be freely moved longitudinally on said guides. The forward end of the tube terminates in a nose, F, to bear against the end of point of 65 the hook C, and on the upper side of the tube a lug, f, is preferably made as a convenient means for sliding the bolt. This bolt may be readily molded and cast without core, it being drawn longitudinally from the mold. The interior of the bolt corresponds to the diameter 70 of the spring to be used.

The bridge b is of shape to pass into the bolt through the slots at the sides, so that the spring H introduced into the bolt and seated 75 against the bridge b will tend to force the bolt forward to the point of the hook, as seen in Fig. 3, but yet yield for the withdrawal of the bolt to open the mouth of the hook.

The parts are put together, and then the 80 hook is bent up into its natural plane and forward of the bolt, as seen in Figs. 1, 2, and 3, which retains the bolt in its position and completes the hook.

By this improvement the construction of 85 this class of hooks is very much simplified, as the parts may be taken as they come from the tumbling-barrel and placed together without any of the usual mechanical operations; hence the cost of the hook is very much reduced, 90 and it possesses all the advantages of the best of this class of hooks—that is, the long barrel which is usually employed, and which is liable to fill with dirt, and thus clog the spring of the hook, which cannot occur in this hook, 95 because the barrel is so open that dirt or foreign substances cannot enter and remain therein to clog its working.

I claim—

The herein-described snap-hook, consisting 100

of the body A, terminating at one end in the loop B and at the other in the hook C, the body constructed with a longitudinal opening, D, provided with guides a a upon its sides, and with the bridge or seat b at the rear, combined with a bolt constructed with a tubular body longitudinally slotted to ride upon said

guides a a, and the spring arranged within the tubular part of the bolt and seated against said bridge, substantially as described.

ALFRED S. HENN.
